INTERFERENCE SUPPRESSION SYSTEM FOR
RADIO RECEIVERS AND THE LIKE

Alan John Henry Oxford, Christchurch, England, assignor to the Minister of Supply, in His Majesty's Government of the United Kingdom of Great Britain and Northern Ireland, London, England

Application July 31, 1947, Serial No. 765,122
In Great Britain November 30, 1945

Section 1, Public Law 690, August 8, 1946
Patent expires November 30, 1965

11 Claims. (Cl. 250—20)

1

This invention relates to the reduction or elimination of interference in radio telephone receivers and other telephone channels due to pulse transmission.

Difficulty has often been experienced in operating communication receivers in close proximity to pulse radar transmitters owing to breakthrough of the pulse into the communication channel.

The interference may be in the form of direct breakthrough at the radar frequency of its harmonics. More frequently it is due to radiation of the higher harmonics of the modulator pulse. Screening is found to be ineffective in many cases where the communication receiver is required to operate close to the radar transmitter.

Whatever form the interference takes, its effect is to introduce a series of pulses at the recurrence frequency of the radar system which at the outset are say, one or two microseconds long, but which due to the limited bandwidth of the receiver, and due to the effects of parasitics etc., produce a note at recurrence frequency having a considerable mark-space ratio and therefore an appreciable power content.

If the receiver be muted for a period embracing the occurrence of the pulse, i. e. from a few microseconds before to a few microseconds after, this pulse can be eliminated but a similar recurrence frequency note is still introduced due to the muting pulse.

It is now proposed that, in addition to the muting pulse referred to above, a number of extra muting pulses should also be supplied equally spaced in time and making in conjunction with the original muting pulse, a continuous train having a frequency higher than the audible limit required in the receiver.

In general it will be found that this entails silencing the receiver for a small proportion of the total time and therefore, it will still function normally.

As it is desirable to avoid any broadening of the incoming interference pulse the muting is done in an early stage of the receiver. As, however, the radiation is such that it may also be picked up in the low-frequency amplifier, this amplifier is preferably also muted simultaneously.

Typical conditions which may arise and which will be assumed in the further description of the invention are as follows.

A representative radar equipment runs at 1000 C. P. S. recurrence with a 1 microsecond pulse. We require to raise the frequency of the interference to about 9000 cycles—in other words we

must introduce 8 additional muting pulses in order that the interference should be inaudible. If these muting pulses are 11 microseconds wide we have a tolerance of plus or minus 5 microseconds to allow for any inaccuracies of timing. The time interval of 9000 cycles is approximately 110 microseconds, so that we are removing 10 per cent of the signal time but this is insufficient to prevent the normal operation of the radio receiver.

The invention is illustrated by the accompanying drawings given by way of example in which:

Fig. 1 is a block schematic diagram of a communication receiver embodying the invention and Fig. 2 is a more detailed circuit diagram of a part of the receiver shown in Fig. 1.

The receiver shown in Fig. 1 comprises R. F. and mixer stages 1, I. F. and second detector stages 2, an output stage 3 and telephones or loud-speaker 4. A muting pulse generator 5 is controlled by lock pulses (corresponding to the interfering pulses) applied over a connection 6 and produces a train of pulses of about 11 microseconds pulse duration and 9000 C. P. S. recurrence frequency which are applied in negative going sense to the control grids or suppressors of the R. F. amplifier valves and the output valve or valves in stages 1 and 3. The effect of the muting pulse is to bias back the controlled valves of the receiver and so mute the receiver for the duration of the pulse. The lock pulse applied over connection 6 may be taken directly from the modulator of the radar transmitter or may be received on an elementary auxiliary receiver 7.

Fig. 2 of the accompanying drawing is a circuit diagram of one form of muting pulse generator 5 for the system of Fig. 1.

Referring to Fig. 2, a pentode valve V1 and associated resistances and capacities including a condenser C1 between anode and ground and a condenser C2 between second and third grids constitutes a transitron circuit generating at its anode a positive going saw-tooth voltage of approximately 9000 cycles per second and at its second or screen grid a train of positive going pulses coinciding with the rapid returns of the anode saw-tooth voltage. This train of pulses at the screen grid is employed for muting the receiver, being fed to I. F. and L. F. stages thereof over connection 8 and a valve stage (not shown) for reversing their sense.

The anode saw-tooth voltage is applied over a coupling condenser C3 to the third grid of a gate valve V2 comprising a pentode having use-

fully-short third-grid base. A diode V4 prevents the third grid of valve V2 being driven positive. Positive lock pulses from connection 6, and representing the interference pulses to be suppressed in the receiver, are applied to the first grid of valve V2.

The amplitude of the pulse appearing at the anode of gate valve V2 consequently depends on the relative timing of the lock pulse and the saw-tooth voltage from the transitron circuit. The anode pulse is rectified by a diode V3 and smoothed in a circuit R1, C4 to yield a positive bias voltage for the third grid of the transitron valve V1. The frequency of the saw-tooth voltage, initially adjusted to about 9000 C. P. S. depends upon the voltage to which the third grid of valve V1 rises and this voltage is determined by the bias connection. Hence the frequency of the saw-tooth voltage is controlled according to the relative timing of the lock pulse and is increased or decreased as necessary to advance or retard the saw-tooth voltage with respect to the lock pulse and hence to maintain the timing of the muting pulses so that one of them symmetrically embraces the lock pulse and others are evenly distributed between successive lock pulses.

More specifically, the voltage of the third-grid of valve V2 alternately rises slowly and falls rapidly giving rise to an inversely changing voltage at the anode of valve V2. If a lock pulse arrives late in the slow part of the cycle, the anode voltage drop is great, the negative bias on the third grid of valve V1 is increased and the frequency of the transitron circuit is increased so that in a subsequent cycle the lock pulse occurs in the fast part. If it occurs early in that fast part, the anode voltage drop in valve V2 is again great and the transitron frequency is further increased. If it occurs late in that fast part, the anode voltage drop is smaller and the transitron frequency falls. Consequently the transitron circuit is controlled in frequency and incidentally in phase so that it is half way through a fast part of its cycle each time a lock pulse arrives. If the anode resistance or the third grid resistance in the transitron circuit is changed to alter the free running frequency, the gate valve and rectifier circuit pulls the frequency in steps from one multiple of the lock frequency to the next.

It will be noted that the lock pulse is not applied directly to lock the phase of the muting pulse generator. Such phase control is undesirable since it tends to synchronise the beginning or end of the muting pulse with the lock pulse whereas it is preferable that the muting pulse should embrace the lock pulse.

The invention may be applied to deal with any interference of a periodic nature provided that (a) the necessary multiplying factor is not excessive: as this factor is increased it becomes difficult after a number of additional muting pulses to ensure that the phase sequence is correct for the next interfering pulse; (b) there is not excessive jitter or irregularities in the interfering pulse; (c) the interfering pulse is not too wide to enable an interval to be provided for signal reception; if this interval becomes small, increased bandwidth in the receiver has to be provided.

I claim:

1. The method of reducing the interference caused in a communication channel by a series of intermittent sharp pulses of audible repetition rate comprising intermittently muting the received signals at a repetition rate of a periodicity that will be substantially attenuated by the chan-

nel and which is higher than and a harmonic of said audible repetition rate, and synchronizing said muting with said pulses so that the received signals are muted for the duration of each sharp pulse.

2. The method of reducing radio interference caused by a series of sharp pulses comprising muting the received signals for the duration of each of said pulses, and further muting said received signals between each of said pulses; each of said muting acts being of short duration as compared to the spaces between adjacent muting acts.

3. The method of reducing interference in a radio receiver caused by a series of sharp substantially equally spaced pulses comprising muting the received signals for the duration of each of said pulses, and further muting the receiver a plurality of times between each of said pulses and at such a rate that all adjacent muting acts are substantially equally spaced in time from each other.

4. The method of reducing interference in a radio receiver caused by a nearby pulse generator, said receiver having radio frequency as well as audio frequency amplification stages, comprising, generating a series of substantially equally spaced muting pulses which are wider than those emitted by the pulse generator as well as have a repetition rate which is greater than and a harmonic of the repetition rate of the pulses from the pulse generator, controlling the phase of the muting pulses to cause a muting pulse to completely overlap each interference pulse, and biasing to cut-off both of said stages by said muting pulses.

5. In a communication channel subject to interference from an adjacent pulse generator which produces pulses at audible rate, means for receiving a fraction of the pulse energy from said generator, means connected to the output of the first-named means for generating a series of pulses at a rate which is greater than and a harmonic of the interference pulse rate, and muting means to apply the output of the last-named means to mute said channel, the second-named means including means to synchronize a series of its pulses which constitute a submultiple of its repetition rate with pulses received at the first-named means.

6. In a radio receiver subject to interference from a nearby pulse generator, a radio frequency amplifier; a mixer connected to the output of said amplifier; an intermediate frequency amplifier connected to the output of said mixer; a second detector connected to the output of said last-named amplifier; an audio amplifier connected to the output of said second detector; means for generating a series of pulses at a rate which is a higher harmonic of the rate of the pulses of the pulse generator; means which receives energy from the pulse generator for synchronizing certain of the pulses of the first-named means with those of the pulse generator; and means for blocking said radio frequency amplifier, said mixer, and said audio amplifier by said series of pulses.

7. In a radio telephone receiver, means for muting said receiver synchronously with interfering pulse signals having components of frequency below the upper audible limiting frequency of said receiver, and means for muting the receiver during further short intervals of time so that any two successive muting operations are

separated by a time which is less than the reciprocal of said limiting frequency.

8. In a communication system including a telephone channel receiver liable to interference by interfering pulse signals having frequency components below the upper audible limiting frequency of the receiver, means for muting said receiver during each occurrence of an interfering pulse, and means for muting said receiver during further short intervals so that the whole muting operation introduces no frequency below said limiting frequency.

9. The method of reducing interference in a superheterodyne receiver comprising the steps defined in claim 3 in which the muting step is accomplished prior to the step of amplifying the intermediate frequency.

10. The device defined in claim 5 in which said channel comprises a radio frequency amplifier stage, a mixer stage, at least one intermediate frequency amplifier stage, and an audio amplification stage, and in which said muting means comprises biasing means connected to negatively bias at least one of said stages that is ahead of the first intermediate frequency amplifier stage.

11. The method defined in claim 1 in which the

muting acts have greater time duration than the received pulses; and in which the synchronizing step causes muting to begin prior to the start of each sharp pulse, to continue for the duration of each such sharp pulse, and to continue for a limited time after the cessation of each such sharp pulse.

ALAN JOHN HENRY OXFORD.
